UNITED STATES PATENT OFFICE.

GEORGE H. DEMORE, OF SYRACUSE, NEW YORK, ASSIGNOR TO OLIVER M. EDWARDS,
OF SYRACUSE, NEW YORK.

WINDING-ROLLER CONSTRUCTION.

1,076,959.

Specification of Letters Patent.

Patented Oct. 28, 1913.

Application filed February 18, 1911. Serial No. 609,447.

To all whom it may concern:

Be it known that I, GEORGE H. DEMORE, of Syracuse, in the county of Onondaga and State of New York, have invented a certain 5 new and useful Winding-Roller Construction, of which the following is a specification.

This invention has for its object a particularly simple and efficient winding roller 10 for raising windows and curtains, etc.; and it consists in the combinations and constructions hereinafter set forth and claimed.

In describing this invention reference is had to the accompanying drawing in which 15 like characters designate corresponding parts in all the views.

Figure 1 is a longitudinal sectional view of a portion of this winding roller. Fig. 2 is an end view thereof, and Fig. 3 is an 20 inner face view of the end member of the roller.

This winding roller comprises, generally, a tubular thin metallic shell 1, a plug 2 within the shell near one end thereof and terminating short of said end, an end member 3 located in said end near the plug and engaging the plug, the end member having a rigid axle 4 projecting from its outer side and means at its inner side for maintaining 25 the end member in position with its axis alined with the axis of the shell.

A suitable winding spring not shown is located within the shell 1 and connected thereto in any suitable manner. As said 35 spring is not pertinent to this invention further description thereof is deemed unnecessary.

The shell 1 is here shown as cylindrical and is formed with a loop portion projecting 40 into the interior thereof and forming a lengthwise internal shoulder 5 and an external groove 6 for receiving the ends of curtains, or chains or cords supporting windows.

45 The plug 2 is usually composed of wood and is formed with a peripheral groove for receiving the internal shoulder 5 and is secured in position in the shell 1 by nipples 7 projected inwardly from the shell into the plug. However, the plug may be secured 50 from movement in the shell 1 in any suitable manner.

The end member 3 is discoidal in form and is fitted within the end of the shell with 55 its periphery engaging the inner circumfer-

ential surface of the shell, said member abutting against the end of the plug at 8 and being provided with a stem 9 projecting axially from its inner side into the plug 2, the stem being usually non-circular in form. 60 The member 3 is also formed with a peripheral notch 10 for receiving the lengthwise shoulder 5 of the shell 1. After the end member 3 has been placed in the shell, it is secured therein by turning inwardly the 65 edge or margin 11 of the end of the shell onto the outer face of the member 3.

A winding roller constructed as described is particularly advantageous, for the reason that the end member is rigidly supported 70 and prevented from becoming twisted so that its axis is out of alinement with the shell 1.

What I claim is:

1. A winding roller comprising a tubular shell, a plug in the shell near one end thereof and terminating short of said end, and an end member arranged in said end of the shell having a rigid axle projecting from its outer side and means projecting from its inner side into the plug, substantially as 75 and for the purpose described.

2. A winding roller comprising a tubular shell, a plug within the shell near one end thereof terminating short of said end, a rigid end member fitting the end of the shell 85 and having an axle projecting from its outer side and means projecting from its inner side into the plug, and means associated with the shell and coacting with said member for holding the same from movement 90 out of the shell, substantially as and for the purpose specified.

3. A winding roller comprising a tubular shell, a plug within the shell near one end thereof terminating short of said end, and a rigid end member fitting the end of the shell and having an axle projecting from its outer side and means projecting from its inner side into the plug, the shell having its end margin turned over onto the outer face of 100 the end member for holding the same for movement out of the shell, substantially as and for the purpose set forth.

4. A winding roller comprising a tubular cylindrical shell, a plug within the shell near 105 one end thereof and terminating short of said end, and a rigid member fitting the end of the shell and having an axle rigid therewith projecting from its outer side, and means projecting from its inner side into 110

the plug, said member abutting against the end of the plug, and the shell being provided with means coacting with said member for holding the same from movement out of the shell and against the end of the plug, substantially as and for the purpose described.

5. A winding roller comprising a tubular shell, a plug fixed in the shell near one end thereof and terminating short of said end, and an end member located in said end of the shell and having an axle projecting from its outer side and means projecting from its inner side into the plug, the edge at said 10 end of the shell being turned inwardly on the outer face of the end member, substantially as and for the purpose described.

6. A winding roller comprising a tubular shell, a plug fixed in the shell near one end thereof and terminating short of said end, and an end member arranged in said end of the shell and abutting against the plug, the end member having an axle projecting from its outer side, and means projecting from its inner side into the plug, and the 20 edge of the shell at said end being turned inwardly on the outer face of the end member, substantially as and for the purpose described.

25 7. A winding roller comprising a tubular cylindrical shell having a lengthwise internal shoulder, a plug within the shell near one end thereof and terminating short of the said end, the plug being formed with a pe-

ripheral groove for receiving the shoulder, 35 and a discoidal end member fitting said end of the shell and abutting against the plug and comprising an axle projecting from its outer side, the edge of the shell at said end being turned inwardly on the outer face 40 of the end member, substantially as and for the purpose described.

8. A winding roller comprising a tubular cylindrical shell having a lengthwise internal shoulder, a plug within the shell near 45 one end thereof and terminating short of said end, the plug being formed with a peripheral groove for receiving the shoulder, and a discoidal end member fitting within said end of the shell and formed with a 50 peripheral notch for receiving the shoulder, said end member abutting against the plug and comprising an axle projecting from its outer side, and a stem projecting from its inner side and into the plug, and the edge 55 of the tubular shell at said end being turned inwardly on the outer face of the end member, substantially as and for the purpose specified.

In testimony whereof, I have hereunto 60 signed my name in the presence of two attesting witnesses, at Syracuse, in the county of Onondaga, in the State of New York, this 14th day of February, 1911.

GEORGE H. DEMORE.
